GLAZING STRIP

Edmund Peremi and Louis Toth, Manhasset, N. Y.

Application June 3, 1936, Serial No. 83,267

14 Claims. (Cl. 189—78)

This invention relates to glazing strips for use in connection with light panels. It is adapted for use in windows either of the casement or the sliding sash type, sky-lights, doors, and, in fact, 5 in any structure in which a pane of glass or other translucent material is employed.

An important object of the invention is to cover and conceal the putty by which a pane is held in its frame, so as to avoid the usual unsightliness 10 of putty.

A further object of the invention is to provide against the drying out of putty and thereby avoid looseness and rattling of the pane after the pane 15 has been in use for a time. Putty, when used with painted frames, or exposed to the air, dries out, hardens, cracks and sometimes falls away in pieces. This is because paint, wood, and air absorb or otherwise consume the oil which is necessary to keep the putty plastic. When putty 20 is used with unpainted, non-corrosive metal and protected from exposure to the air the putty remains soft indefinitely. In accordance with the present invention putty engaging portions of the frame and glazing strip are formed of non-cor- 25 rosive metal which does not require to be painted and which is not painted.

The invention aims to provide a thin flexible covering strip for concealing and protecting the putty, which can be sprung into place after the 30 putty is applied. In certain preferred embodiments the glazing strip is provided with a flange or lip for engaging the edge of the pane and for bearing against the pane edge with yielding pressure.

35 It is an important feature of the invention that the glazing strip is sprung into place and that it remains securely in place without the aid of screws or other extraneous holding means.

The use of the putty covering strip as disclosed 40 herein enables the manufacturer to glaze the sash or window at the factory so that the glass is held permanently in position when shipped, and the necessity of having an experienced glazier in the field to do the glazing is avoided. It is a 45 point, however, that the glazing strip may be sprung free when a broken pane has to be replaced, and may be reapplied in the same simple manner in which it was applied in the first instance.

50 Other objects and advantages will hereinafter appear.

In the drawing forming part of this specification and illustrating several preferred embodiments of the invention,

55 Fig. 1 is a fragmentary view showing a corner

of a window light embodying features of the invention;

Fig. 1a is a sectional transverse view showing the glazing strip of Fig. 1 separate from the other window elements;

Fig. 2 is a fragmentary sectional view illustrating another embodiment of the invention;

Fig. 3 is a view similar to Fig. 2 illustrating a third embodiment;

Fig. 4 is a view similar to Fig. 2 illustrating a 10 fourth embodiment, the section being taken on the line 4—4 of Fig. 5 in the direction of the arrows;

Fig. 5 is a fragmentary sectional view of the structure shown in Fig. 4, the section being taken 15 on the line 5—5 of Fig. 4 looking in the direction of the arrows and being shown broken away intermediate its ends for compactness of illustration;

Fig. 6 is a view similar to Fig. 2 illustrating still 20 another embodiment of the invention; and

Fig. 7 is a fragmentary sectional view taken on the line 7—7 of Fig. 6 looking in the direction of the arrows.

While the several views show only fragmentary 25 portions of window lights it is to be understood that in each instance the frame members bounding a light opening would be made to present the same contour toward the light opening, regardless of variations in the body structure of the 30 members. In a muntin bar this external contour would be duplicated at opposite sides of the bar.

In Fig. 1 disclosure is made of a frame 1 which carries a pane 2. The frame 1 comprises a web 3 at the inner side of the window which extends 35 parallel to the plane of the pane 2 at all four sides of the pane opening. At the outer side of the web 3 and at some distance below the top of the web provision is made of an outwardly extending flange 4 which extends completely around 40 the pane opening and bounds the space in which the pane is received. The frame 1 also includes an outwardly extending web 5 and a web 6 which extends parallel to the plane of the pane 2. The webs 5 and 6 extend completely around the pane 45 opening at all four sides thereof. A lip 7 extends upward from the outer extremity of the web 5 and is inclined inward toward the pane 2.

Putty 8 is first applied in the frame space bounded by the webs 3, 5 and 7, and the pane 2 50 is then put into place, being mashed into the putty which is located above the flange 4 and outside the web 3. A glazing strip 9 of thin flexible metal is then pressed into place.

The glazing strip comprises an inwardly ex- 55

- tending web 10 which is forced beneath the flange 4. The glazing strip also comprises a web 11 which extends parallel to the pane 2 and in a position to overlie a margin of the pane. The 5 glazing strip also includes a downwardly and outwardly inclined web 12 which is formed with a shoulder 13 at its lower end, and a marginal lip 14 which extends downwardly and outwardly from the shoulder.
- 10 When the web 10 of the glazing strip has been forced into place the strip is buckled sufficiently to force the lip 14 over the lip 7 of the frame and to spring the lip 14 down to the position shown in Fig. 1, so that it bears against the inner, 15 inclined face of the lip 7. The excess putty which has been squeezed out is then wiped off. When all four glazing strips have been applied the exterior of the window presents nothing but metal and glass to view.
- 15 The frame and the glazing strip are both composed of non-corrosive metal which is left unpainted so that the oil in the putty is not absorbed and the putty is permitted to remain plastic. The glazing strip covers the putty and protects it 20 from the air, and thereby aids the retention of plasticity by the putty.

Should the pane become broken, the glazing strip 9 can be conveniently removed by inserting a knife or other sharp instrument into an angle 30 15 which is intentionally provided for that purpose between the shoulder 13 and the upper edge of the frame lip 7.

In the form of the invention shown in Fig. 2 the light comprises a pane 16 and a frame 17. The frame includes an inner web 18 which extends 35 parallel to the plane of the pane, an outwardly extending lip 19 for engaging the inner face of the pane, and an outwardly extending web 20. The outer end 21 of the web 20 is inclined downward. The frame also includes an outer web 22 which extends parallel to the plane of the pane and which terminates in an inturned flange or 40 lip 23. The frame members 18, 19, 20, 21, 22 and 23 define a putty receiving pocket which 45 extends completely around the pane opening. After putty has been put into this pocket the pane 16 is pressed into the position indicated and additional putty is put into the pocket to substantially fill the pocket. A thin flexible glazing strip 50 24 of non-corrosive metal is then put into place as shown in Fig. 2.

The glazing strip comprises a web 27 which extends parallel to the pane and overlies a margin thereof, a downwardly and outwardly extending web 28 for covering, concealing and protecting the putty, an inwardly extending lip 29 and a downwardly extending lip 30. The lower margin of the web 27 comprises alternate pane-engaging segments 25 and upright segments for 55 engaging the web 20. The bending of the segments 25 is performed after the dimensions of the pane are known, the line of the bend being selected with reference to the known dimensions of the glass. Thus the plane of the segments 25 may be set inward more or less from the edge line of the segments 26 as required, to assure a snug fit of the pane. After the web 27 has been forced 60 into place the glazing strip is buckled and the lip 30 is sprung behind the frame flange or lip 23. The flange 29 forms an angle with the upper surface of the flange or lip 23 into which a knife or other sharp instrument can be inserted for 65 removing the glazing strip when desired. As in the form of Fig. 1 the metallic parts are all of 70 non-corrosive metal and are unpainted. This is

also characteristic of the other forms to be described.

In the form illustrated in Fig. 3 the light comprises a pane 31, a frame 32, a glazing strip 33 and putty 34. The frame is composed of channel shaped members, each having an inner web 35 that extends parallel to the pane. Each channel shaped frame member is formed with a dove-tailed groove 36. The glazing strip 33 comprises an inwardly extending web 37 for engaging the inner boundary of the dove-tailed groove, an upwardly extending web 38 for overlying a margin of the pane, a downwardly and outwardly extending web 39 for covering and concealing the putty, a shoulder or flange 40, and a retaining lip 41 which is sprung behind the shoulder at the outer boundary of the dove-tailed groove. Fingers 42 are struck at intervals from the web 37 and bent in a direction so that when applied to the frame they will extend across an edge of the pane and 45 support the pane. The assembly of the parts is generally the same as that of the forms previously described. The fingers 42 are bent after the dimensions of the pane are known.

In the form of the invention shown in Figs. 4 50 and 5 the light comprises a pane 43, a frame 44, putty 45 and glazing strips 46. The illustrated frame member 44 is of hollow construction and includes an inner web or flange 47 which extends parallel to the plane of the pane. An upwardly 55 and inwardly extending lip 48 is provided at the outer extremity of the frame for retaining the putty and glazing strip in place. The glazing strip comprises, a web 51 which extends parallel to the plane of the pane and overlies a margin of the pane, a downwardly and outwardly extending web 52, a shoulder 53, and a retaining lip 54. The lower margin of the web 51 is divided into alternate pane engaging fingers 49 and supporting feet 50. The assembly of the parts is effected 60 in the same manner as that already described for the other forms.

In the embodiment of Fig. 6 the light comprises a pane 55, a frame composed of members 56, putty 57, and glazing strips 58. The frame comprises an inner web 59 having an outwardly offset flange 60 at its upper extremity, an outwardly extending web 61, and an outer web 62 which extends parallel to the plane of the pane. At the upper side of the web 61 provision is made of an upwardly and inwardly extending retaining lip 63 at the outer edge of the frame, and of an upwardly and inwardly extending lip 64 between the edges of the web 61. The glazing strip comprises a web 67 which extends parallel to the pane and across a margin of the pane. The lower margin of the web 67 is divided into alternate pane engaging fingers 65 and supporting feet 66. The glazing strip also includes outwardly extending webs 68 and 69, a shoulder 70, and a retaining lip 71. The feet 66 extend outward and rest on the upper edge of the lip 64 and lie substantially in the plane of the fingers 65. As before, however, the fingers 65 are bent after the pane dimensions are known. The lip 64 extends close 75 to the edge of the pane and assures the tight packing of the putty all around the pane margin.

While we have illustrated and described in detail certain preferred forms of our invention, it is to be understood that changes may be made 80 therein and the invention embodied in other structures. We do not, therefore, desire to limit ourselves to the specific constructions illustrated, but intend to cover our invention broadly in whatever form its principle may be utilized.

We claim:

1. In a light, in combination a pane, putty surrounding and engaging the edges of the pane, a frame composed of channel members, each forming a putty channel and including a pane seat web and a retaining flange, and a glazing strip of thin flexible non-corrosive metal for covering the putty, including a web extending across the plane of the pane, a pane covering web spaced from the pane, an outwardly extending web to extend over the putty, and a retaining lip adapted to be sprung over and held in place by the retaining flange of the frame.

2. In a light, in combination a pane, putty surrounding and engaging the edges of the pane, a frame composed of channel members, each forming a putty channel and a pane seat, and a glazing strip of thin flexible sheet metal having opposite edge portions adapted to be caught 10 in the channel and an intermediate body portion for covering the putty and bearing against a pane margin, and bendable, pane-supporting fingers.

3. In a light, in combination a pane, putty surrounding and engaging the edges of the pane, a frame composed of channel members, each forming a putty channel and a pane seat, and a metallic putty covering strip comprising a marginal web divided into alternate supporting feet 20 and bendable, pane-supporting fingers, the latter adapted to be inserted in bearing relation across an edge of the pane, and an opposite marginal edge adapted to be sprung into the putty channel and trapped therein.

4. In a light, in combination a pane, putty surrounding and engaging the edges of the pane, a frame composed of channel members, each forming a putty channel bounded at opposite sides by a pane seat web and a retaining lip, the 30 retaining lip having a surface at the side facing the pane seat web which is inclined to extend toward the pane seat web, and a putty covering metallic strip having opposite marginal portions adapted to be trapped in opposite sides of the 40 putty channel, one of said marginal portions comprising alternate supporting feet and bendable, pane-engaging fingers, and an intermediate body portion spaced from the pane to overlie the putty and cover a pane margin in opposed relation to the pane seat web.

5. In a light, in combination a pane, putty surrounding and engaging the edges of the pane, a frame composed of channel members, each forming a putty channel bounded at opposite sides by a pane seat web and a retaining lip, the retaining lip having a surface at the side facing the pane seat web which is inclined to extend toward the pane seat web, and a putty covering metallic strip having opposite marginal portions 50 adapted to be trapped in opposite sides of the putty channel, one of said marginal portions comprising alternate supporting feet and bendable, pane-engaging fingers, and an intermediate body portion spaced from the pane to overlie the 60 putty and cover a pane margin in opposed relation to the pane seat web, the covering strip and the retaining lip having opposed shouldered portions which extend divergently outward so that a tool can be conveniently inserted between 70 them to pry the covering strip free.

6. In a light, in combination a pane, putty surrounding and engaging the edges of the pane, a frame member comprising a pane seat web, a pane supporting flange extending outward therefrom, an outwardly extending transverse

web, and an upwardly extending retaining lip, and a putty covering strip formed of thin flexible metal having a marginal web adapted to be inserted beneath the pane supporting flange, an opposite marginal web or lip adapted to be sprung around and trapped against the retaining lip, and an intermediate body portion arranged to extend across a marginal portion of the pane.

7. In a light, in combination a pane, putty surrounding and engaging the edges of the pane, a frame member comprising an inner web disposed to extend in the direction of the pane plane, an outwardly extending pane seat flange at one edge of said web, an outwardly extending web, and an outer web extending substantially 15 parallel to the pane plane, the last mentioned web terminating in an inwardly extending retaining lip, and a putty covering strip of thin flexible metal having a marginal web divided into alternate supporting feet and bendable, 20 pane-supporting fingers, the latter adapted to extend across an edge of the pane in bearing relation thereto, feet for engaging the outwardly extending web of the frame member, an opposite marginal web or lip adapted to be sprung 25 around and trapped against the retaining lip, and an intermediate body portion arranged to extend across a marginal portion of the outer face of the pane.

8. In a light, in combination, a frame member 30 comprising an inner web disposed to extend parallel to the pane plane, and an outwardly extending web having a dove-tailed groove in its face which is toward the light opening, and a flexible metallic putty covering strip comprising 35 opposite marginal web portions caught in the dove-tailed groove one of said marginal portions comprising alternate supporting feet and bendable, pane-engaging fingers, and an intermediate 40 body portion adapted to cover a marginal portion of the pane.

9. In a light, in combination a pane, putty surrounding and engaging the edges of the pane, a frame member comprising an inner pane seat web disposed to extend parallel to the pane plane, 45 an outwardly extending web and an outer retaining web inclined toward the pane seat web, and a putty covering strip having a marginal web divided into alternate supporting feet and bendable, pane-supporting fingers, the latter adapted 50 to be inserted across a pane edge in bearing relation thereto, an opposite marginal web or lip adapted to be trapped against the retaining lip, and an intermediate body portion for covering a marginal portion of the pane at the outer side thereof.

10. In a light, in combination, a pane, putty surrounding and engaging the edges of the pane, a frame comprising an inner seat web for engaging a pane at a distance inward from the pane 60 edge, the web being offset away from the pane plane opposite the extreme marginal portion of the pane to provide a putty pocket, an outwardly extending web, and a retaining lip, and a putty covering strip of thin flexible metal having opposite marginal portions caught against the pane edge and against the retaining lip respectively, one of said marginal portions comprising alternate supporting feet and bendable, pane-engaging fingers, and an intermediate body portion 70 for covering a marginal portion of the outer face of the pane.

11. In a light, in combination, a frame comprising an inner seat web, an outwardly extending web, a putty retaining lip extending from the 75

outwardly extending web toward the pane area adjacent the pane plane, but terminating short of the pane area, and an outer retaining lip, and a flexible metallic putty covering strip comprising a marginal web divided into alternate supporting feet and bendable, pane-supporting fingers, the latter adapted to extend across a pane edge in bearing relation thereto, the supporting feet extending outward and adapted to rest on the first putty retaining lip, a second marginal web adapted to be trapped against the outer retaining lip, and an intermediate body portion for covering a marginal portion of the outer face of the pane.

12. In a light, the combination with a pane, of a frame forming a pane seat and a putty channel surrounding the light opening, putty in the channel engaging and surrounding the pane edges, and a metallic covering shell concealing the putty around the entire perimeter of the pane consisting of thin flexible metallic strips including portions which are interfitted with the frame and resiliently trapped in place.

13. In a light, the combination with a pane, of a frame of non-corrosive unpainted metal defining a seat for the pane and a putty channel en-

gaging and surrounding the pane edges, putty in the channel and a putty cover composed of thin unpainted flexible strips of non-corrosive metal held in interlocking relation with the frame for concealing the putty and protecting it from the elements.

14. In a light, in combination, a frame comprising an inner seat web, a web extending outwardly for a substantial distance beyond the plane of the pane, a putty retaining lip extending from the outwardly extending web toward the pane area, said outwardly extending web and putty retaining lip forming a putty channel capable of receiving and holding a substantial quantity of putty, said putty channel surrounding the light opening, putty in the channel engaging and surrounding the pane edges, and a metallic covering shell concealing the putty in said putty reservoir around the entire perimeter of the pane, said metallic covering shell consisting of thin, flexible metallic strips including portions which are interfitted with the frame and resiliently trapped in place.
